SHOE-POLISHING MACHINE.

No. 868,813.

Specification of Letters Patent.

Patented Oct. 15, 1907.

Application filed December 22, 1906. Serial No. 349,128.

To all whom it may concern:

Be it known that we, JOSEPH M. WOLKOSKY, FRANK MAGIDSON, SAMUEL PRINTZ, and ABRAHAM WOLKOSKY, residents of Irwin, in the county of Westmoreland and State of Pennsylvania, have invented certain new and useful Improvements in Shoe-Polishing Machines, of which the following is a specification.

This invention relates to a machine for cleaning and polishing shoes, and is directed primarily to certain improvements in the machine for which on June 16, 1906, we made application for Letters Patent, Serial No. 322,012. In the machine disclosed in that application, two brushes are arranged to move toward and from each other at opposite sides of an interposed 15 shoe, while a third brush is caused to operate on the front or toe portion thereof.

In the improved machine of this application, we have provided opposite groups of individually rotating brushes for operating, one at a time, on opposite 20 sides of a shoe; also a group of brushes for the front or toe portion. In connection with these brush groups, we have provided simple and effective mechanism for causing the groups to shift automatically, so that the cleaning or scrubbing brushes are always presented first for preparing the surface to be shined, and the polishing brush last for developing the shine.

The invention also embodies various improvements in the driving or actuating mechanism.

In the accompanying drawings, Figure 1 is a side 30 elevation of the machine excepting the uppermost part thereof which is shown in Fig. 1^a, the outer casing being shown in section in both views. Figs. 2 and 2^a are similar views of the opposite side of the machine, Fig. 2 being on the broken line 2-2 of Fig. 4. Fig. 3 is a front elevation of the interior mechanism. Fig. 4 is a plan view of the brushes and their actuating mechanisms. Fig. 5 is a detail view of the toe-brush mechanism. Fig. 6 is a front elevation of the side groups of brushes, showing them in inward or operative 40 position in solid lines, and in outward position in dotted lines. Figs. 7 and 8 are detail views of the governor shaft and attendant mechanism, Fig. 7 being on line 7-7 of Fig. 8. Fig. 9 is a detail view of the latch mechanism for holding the foot rest in lowered position, the latch being shown projected as in Fig. 2 for holding the rest depressed. Fig. 10 is a similar view, showing the latch retracted as in Figs. 1 and 4. Fig. 11 is a vertical sectional view of the air-controlling valve.

50 The mechanism is inclosed in a casing which consists of the upright portion 2 and base portion 3, the

latter having an opening in its top which is normally closed by the depressible foot rest 4, carrying the shoe form or holder 4^a.

Within frame 3 are two series or groups of side 55 brushes, the groups being movable bodily toward and from each other for operating on opposite sides of a shoe. We here show three brushes in each group, viz. the cleaner or scrubber 5, a dauber or polish spreader 6, and a shining or polishing brush 7. These brushes 60 are rotatably mounted in holder 8, and this holder is journaled on shaft 9 extending through an oscillating carrier 10, the latter being mounted at its lower end to swing on shaft 11.

Secured to shaft 9 is a gear wheel 12, and meshing 65 therewith are the gears 13 secured to and rotating with the brushes. Shaft 9 is driven by chain 14 extending from a gear wheel on shaft 11. Thus, the several brushes rotate continuously while the machine is in operation, and it is only necessary to provide means 70 for causing them to move successively to operating position by causing the group holder 8 to turn on shaft 9. Owing to the manner in which the brushes are individually rotated, holder 8 tends constantly to turn with drive gear 12 in the direction indicated by 75 arrow a Fig. 3, and this turning tendency is relied on for presenting first one and then another of the brushes to operative position.

The mechanism for preventing holder 8 from rotating consists of a circular plate 15 secured to the inner 80 end thereof, this plate having three notches 15', one for each brush. Normally engaging one or another of these notches is the spring-held latch 16 pivoted to the inner end of carrier frame 10. A lever mechanism, presently to be described, operates to momentarily release the latch at certain periods in the operation of the machine so that the brush groups may shift automatically, as above described.

At the base of each carrier-frame 10 is a transverse arm 17, having one end normally drawn upward by a 90 spring 18, the tendency of these springs being to tilt the brush groups inward, or toward each other, with the active brushes in contact with the shoe, such inward position being shown in full lines in Fig. 6. Extending beneath the opposite or inner ends of each of arms 95 17 is the elongated lever 19 which parallels the base of frame 10, being fulcrumed at its front end at 19', and at its rear end deflected upwardly and extended backward, as at 19'', where it is engaged by a cam 20 on shaft 21. The operation of shaft 21, presently to be 100 described, is so timed as to raise cams 20 and elevate levers 19 at those periods in the operation of the ma-

chine when the brush groups are tilted outwardly or away from each other, this movement being opposed by springs 18.

Paralleling and slightly forward from shaft 21 is shaft 22, to which shafts 11 are geared as shown, shaft 22 being driven from a main drive shaft in the upper portion of the machine, as will presently appear. Mounted to oscillate on shaft 22 are the upright arms 23 of the carrier for the group of front or toe-brushes, 10 the horizontal upper portion 24 of the carrier frame being hinged on shaft 25 journalled in the upper ends of arms 23. Journalled in the outer portion of frame 24 is shaft 25', and rotatably mounted midway between its ends on this shaft is frame 26. Journalled in one end 15 of said frame is the scrubbing or cleaning brush 27, and in the opposite end the polishing brush or buffer 28, the shaft of each of these brushes carrying a gear 29, which meshes with a gear wheel 30 on shaft 25'. The tendency of gears 29 to turn with drive gear 30 is availed of, as in the case of the side groups of brushes, for turning holder 26 and reversing the position of brushes 27 and 28. For holding frame 26 against rotation, a stop projection 31 is extended from each end thereof which 20 engages the spring-held latch 32 pivoted to frame 24. The turning tendency of frame 26 is such as to carry its rear end downward, and hence latch 32 is so constructed as to lock the frame against such movement. However at the times when it is desired to shift the brushes, latch 32 is operated by a lever 33 as will be presently 25 described, the latch at such times being so turned as to release stop 31 and free frame 26. Latch 32 is preferably formed with two stop-engaging shoulders or faces, so that when frame 26 turns stop 31 momentarily engages shoulder 34, and then settles into engagement with hook of 34' which forms the permanent 30 hold until the latch is operated by lever 33. The turning movement of frame 26 is thus arrested, and the jar incident to stopping it is distributed between the two points.

40 Shaft 25' is rotated by a chain 35 extending from shaft 25, and in turn the latter is driven by chain 36 extending upwardly from shaft 22. The carrier frame for brushes 27 and 28 consisting of parts 23 and 24, is turned forward against the pull of spring 23', by an upward lever 37, fulcrumed between its ends at 37', and at its upper end engaged by cam 38 on one of the shafts of a train of gearing in the upper portion of the machine, hereinafter described.

The depressible foot rest 4 maintains a constant horizontal position, and when lowered places the sides of the shoe between the upper active brushes of the side groups, the side brushes being always in the same position or at the same elevation when active. The depressed position of the shoe holder is also such as to 50 cause the front group of brushes to move forward and be slightly raised or tilted owing to the forward or active brush climbing upward slightly on the shoe and exert sufficient pressure thereon for effective work. Rest 4 is sustained by a standard or bracket 39 depending from its under side, to which is pivoted the forward ends of the two hinge-arms 40 and 41, pivoted at their rear ends to standard 42. A spring 43 connected to the rear end of arm 41, together with springs 44 and 44', operates to resist the downward movement of the foot 55 support and raises the same when free to do so. When

the rest is depressed, standard 39 bears on the bottom of the casing and forms a stop. When raised, the foot or link 45, pivoted to arm 41, is drawn back and drops behind a lug 46 on the bottom of the casing and locks the platform in raised position. Link 45 swings 70 forward as the foot support lowers, and is drawn backward when the latter is raised by spring 45'.

When the foot support is depressed, the forward end of hinge arm 41 is engaged by the spring latch 47 which locks it in lowered position. This latch operates like 75 an ordinary spring latch of a door, the stem 47' thereof being connected to lever 48. To one end of this lever is connected a rod 49 having a hook 49' at its rear end, for lifting the lower extremity of link 45 over lug 46, thereby releasing the foot rest for its downward movement. To the other end of lever 48 is connected rod 50 which extends rearward to frame portion 2 where it connects with bell-crank lever 51 which, in turn, is connected to upwardly extending spring-rod 52, the latter at its upper end uniting with the vertically sliding bar 53. A spring 48' connected to lever 48, together with spring-rod 52, tend to hold bar 53 lowered.

When bar 53 is in elevated position the mechanism is inactive, the bar being held raised by the combined lever and dog 54 engaging a notch in one edge thereof, 90 as shown in Fig. 8, the lever being held normally in engagement with the bar by spring 55. The disengagement is effected by depressing the outer end of lever 54 by rod 56 which extends into the upper portion of casing 2 where it is engaged by one arm of 95 bell-crank lever 57, the opposite arm being engaged by the longitudinally movable rod 58 of the check or coin controlled mechanism. The latter consists of a suitable guide-casing 59 which intersects the check or coin chute 60, leading to receptacle 61, together with the 100 outwardly projecting push-rod 62 carrying check holder 63 which moves over ledge 64. When the check or coin is dropped in chute 60, it lodges in receptacle 63, and projects sufficiently therefrom to engage rod 58 and push the latter inward along with the push rod, 105 thus oscillating lever 57; depressing rod 56; and disengaging lever 54 from bar 53. The mechanism is thus set in motion as will be presently explained, this having been accomplished by the time the coin has moved inward over ledge 64, whereupon the coin drops into 110 receptacle 61. Rod 62 is returned to outward position by spring 62'. The stem of a register R may be arranged beneath lever 57 for registering each operation of the machine.

The machine is operated by an electric motor 65 115 positioned in the upper portion of casing 2, and included in the motor circuit C is a circuit breaker 66, the movable member 66' of which is loosely connected to the upper end of bar 53, so that when said bar is raised the circuit is broken, and the lowering of the bar, as 120 when operated by the check or coin mechanism, closes the circuit. The circuit is also in control of a second breaker 67, operated by the depressible foot-supporting mechanism, so that the circuit is not fully closed and the motor started until the foot rest has been lowered, 125 with the shoe in position between the brushes. When the coin or check is inserted, lever 54 operated, and bar permitted to lower, as above described (this action being in response to the pull of spring-rod 52 and spring 54), lever 48 is oscillated, and hook-rod 49 moved lon- 130

itudinally, thereby carrying link 45 forward over lug 46 and permitting the foot rest to lower under the weight of the operator's foot. When fully lowered, circuit breaker 67 is closed, whereupon the motor is started 5 and the machine set in motion.

Power from the motor is transmitted to the various portions of the mechanism by a train of gearing which I will now describe. The gearing is supported by suitable brackets in the upper portion of casing 2, in front 10 of bar 53 and its associated parts. The uppermost shaft 68 thereof comprises the main power transmitting shaft, being connected by belt 68' with the motor. One end of this shaft is geared directly to base shaft 22 by chain or belt 59 for rotating the side brushes. Beneath shaft 68 is a series of horizontal shafts 69, 70, 71, 72, and 73, arranged one above the other as shown. Shafts 68 and 69 are connected by the two belts or chains 74 and 74', shaft 69 carrying balance wheel 75 at one end, and at its opposite end wheel 76 from which 20 projects stop 77. Shafts 69, 70, 71, 72, and 73 are connected by suitable gearing as shown, one purpose of the intermediate shafts 70, 71, and 72 being to reduce the speed transmitted to shaft 73, which latter we term the time or governor shaft. A further duty of shaft 25 71 is to rotate cam 38 which operates lever 37, as above described, for moving the toe-brush carrier toward the shoe. Extending from a gear on shaft 71 is chain 21 which drives base shaft 21 for operating levers 19.

Governor shaft 73 carries two series of radially projecting pins 78 and 79, the former for actuating the mechanism which releases the groups of side brushes, and projections 79 for similarly releasing the group of toe-brushes, so that the brushes of each group may shift or change their position.

35 The mechanism, operated by projections 78, for actuating latches 16 of the side brush groups, consist of a rock-shaft 80 having an upwardly projecting finger 81, engaged and moved by projections 78 successively. Depending from opposite ends of shaft 80 are similar fingers 82 which engage the rear edges of upright levers 83, each of which is fulcrumed at 83' to a horizontal lever 84 having its outer end 84' beneath latch 16. The upper portions of levers 83 are held normally retracted by spring 83''. Each of levers 83 extends 45 downward below horizontal lever 84 and in front of base shaft 21, where the edge of the lever has a notch 85' which is in the plane of, but normally out of the path of, a pin 85 carried by shaft 21. It is only when the spring-held upper end of lever 83 is moved into the 50 path of projections 85 that it is engaged thereby, when levers 83 and 84 are raised and latch 16 is oscillated by lever-extremity 84' and momentarily disengaged from its notch in plate 15 of brush holder 8, thus permitting said holder to turn and shift the group, moving one brush out of, and the next brush into, operative position. The period of disengagement of latch 16 is so short that it is ready to engage the next notch 15' and lock the group in the next position.

55 Projections 79 on governor shaft 73 engage, successively, the upper end of and oscillate a lever 33 against the pull of spring 33'. When toe-brush frame 24 is in backward position, the lower end of lever 33 is immediately behind the spring latch 32, as shown in dotted lines in Fig. 5, and only operates the latter when 65 said lever is oscillated by one of projections 79, when

its lower end is moved outward into engagement with and so turns latch 32 as to release stop 31 and permit the brush-holder to turn on shaft 25'. But the almost immediate disengagement of the lever and latch causes the latter to retract, first partially so that the next approaching stop engages the upper surface 34 of the latch, and then fully for the more permanent engagement with surface 34', as before explained. Also secured to governor-shaft 73 is head 86 from which projects spring arm 87 into the plane of notch 53' in the edge of slide 75 53, so that when the machine approaches the completion of its operation (shaft 73 making one complete rotation for each complete operation), finger 87 enters notch 53' and engages and raises bar 53, thus opening circuit breaker 66 and stopping the motor, and at the same time permitting lever-dog 54 to engage and hold said bar in elevated position. As a further result of the raising of this bar, lever 48 is oscillated, thereby releasing the spring latch 47 from hinge-arm 41, whereupon the foot rest is raised by the springs connected to 80 its hinge-arms, and is automatically locked in raised position by link 45 being turned behind lug 46. At the same time circuit breaker 67 is opened.

Spring arm 87 remains in engagement with notch 53' until lever lug 54 is again oscillated by the depression 90 of rod 56 for the next operation of the machine. When lever 54 is so depressed, curved link 88 connected thereto moves laterally an arm 89 which engages and springs arm 87 out of notch 53', and bar 53 is free to drop. Spring 89' holds arm 89 normally in horizontal 95 position, a projection 89'' limiting the movement of the arm by the spring. Arm 89 is thus pivoted and spring-held so that its outer end may be raised by spring arm 87 when the latter is raising the bar 53, the position of arm 89 being inward or at one side of bar 87 only when 100 the bar is engaged by lever dog 54, as will be understood.

To stop and lock the train of gearing in the same position each time the machine comes to rest in order that the several parts will be in proper position for starting, 105 and thus securing the proper sequence of operations, a lever 90 is so fulcrumed that its lower angular end 90' is oscillated in and out of the path of stop 77 on wheel 76, being in the path of and in engagement with said stop when the mechanism comes to rest. The upper end 111 of this lever extends past lever-dog 54 and its outer edge is engaged by lug 54' of the latter, the arrangement being such that when lever 54 is depressed, as when operated by the check controlled mechanism, lever 90 is oscillated against the pull of spring 91 and its lower 115 end moved and held out of path of stop 77.

The liquid polish is contained in three cans or reservoirs, two of these cans 92 being secured to the inner ends of oscillating brush carrier 10, and the third can 93, fixed centrally at the front of frame portion 3. These 120 cans are equipped with atomizers 94 of usual form, with their discharge tubes 95 extended toward the shoe holder in such position as to spray the polish very effectively over the entire surface to be shined. Air under pressure is supplied to the atomizers of reservoirs 125 92 through tubes 96, and a similar tube 97 extends around the casing of the machine to the atomizers of reservoirs 93. Tubes 96 and 97 connect with head 98, from which tube 99 extends upwardly to valve 100, the latter in turn being connected by pipe 101 to air 130

reservoir 102. Valve 100 is normally closed to the passage of air, but is opened momentarily when stem 103 thereof is raised by cam 104 on governor shaft 73. The air valve is thus opened only once during each complete operation of the machine, and at the proper time for applying the liquid polish to the shoe. An air pump 105 has its piston connected to crank 106 of shaft 68, the pump being pivoted to oscillate at 105' on a suitable support (not shown) secured to casing 2. A tube 107 connects the pump cylinder with reservoir 102, and by this means a supply of air under pressure is maintained in the latter. The reservoir may be provided with safety valve 108 to prevent excessive air pressure.

While the general operation of the machine will be understood from the foregoing description, a general review of its principal features, and their sequence, may make the same more clear. Each time the machine comes to rest at the completion of a polishing operation, the cleaning or scrubbing brushes 5 of the opposite side-groups are in operative position, and the same is true of cleaning brush 27 of the front or toe-group, all three of these groups being at such time in backward or separated position, as will be understood. When the operator places his foot upon the foot rest, the latter is locked in raised position and cannot be depressed until a check or coin is inserted at the top of the machine, and the push-pin mechanism operated in order to release bar 53 and permit it to lower. The lowering of this bar closes the upper circuit breaker, and also releases link 45 so that the foot rest may lower under the weight or pressure of the foot, and when the latter is completely lowered it is engaged and held by spring catch 47, and at the same time circuit breaker 67 is closed, thus completing the circuit to the motor and setting the mechanism in motion. Cams 20 on base shaft 21, and cam 38 on shaft 71 are so arranged as to cause the side groups of brushes to move into contact with the shoe alternately with the front group, the side groups being in outer or separated position when the front group is in operative position, and vice-versa. The shoe is first cleaned and prepared for the polish by the cleaning or scrubbing brushes, these constantly rotating brushes being preferably moved twice in and out of contact with the shoe before one of projections 78 on governor-shaft 73 operates to release the side groups and permit them to shift, thus turning the daubing or polish-spreading brushes 6 into position. Simultaneously with this shifting operation, cam 104 momentarily opens air-valve 100 and the cleaned shoe is sprayed with liquid polish. The side groups are then caused to move in and out of contact with the shoe, preferably three times, thus spreading the polish and developing the shine to a considerable extent. Meanwhile, brush 27 has alternated with the side brushes, no shift having occurred in the front group. After daubers 6 have operated as described, the side groups are again caused to shift, bringing the polishing brushes 7 into operative position, and at the same time the shifting mechanism for front or toe-group is brought into play, and the polishing brush or buffer 28 thereof is placed in shoe-engaging position. The shining brushes preferably move back and forth twice, and this marks the completion of the operation, the movement of the machine being stopped by the raising of the bar 53

by spring arm 87 and opening circuit breaker 66. The foot-rest is then released by latch 47, and the mechanism stops, this occurring even though the operator should not immediately raise his foot in response to the upward pressure of the shoe holder springs. By thus employing two circuit breakers, it is impossible for the machine to be set into motion before the shoe is in proper position and the foot-rest locked in that position, and the stopping of the mechanism at the completion of the operation is beyond the control of the operator, being accomplished automatically, while the shoe-support is still depressed.

The mechanism for shifting the brush groups is so arranged that the brushes cannot turn or shift excepting when in backward position or out of engagement with the shoe. All of the brushes of the side groups are preferably formed of bristle which may be of such shape or contour as to do the most effective work. The first or cleaning brush of the toe-group is also formed of bristles, and the shining or polishing brush or buffer 28 is formed, preferably, of a spool-shaped body 28' having a flexible covering 28" of felt, flannel, or other suitable material, the latter serving best to develop the shine on the toe portion of the shoe.

While we have shown and described the preferred arrangement of mechanisms, and the sequence of operations thought most desirable, it will be understood that the same may be varied without departing from the spirit and scope of the invention as defined by the appended claims.

We claim:

1. In a shoe polishing machine, a carrier movable toward and away from a shoe, a support rotatably mounted on the carrier, a latch device for holding the support immovable on the carrier, a plurality of individually moving brushes carried by the support, brush-moving mechanism, and means actuated by the brush moving mechanism when the support is away from the shoe for releasing said latch device and permitting the brush support to shift.

2. In a shoe polishing machine, a carrier movable toward and away from a shoe, a support rotatably mounted on the carrier, a latch device for holding the support immovable on the carrier, a group of individually rotating brushes on the support, brush rotating mechanism, and means actuated by the brush rotating mechanism when the support is away from the shoe for releasing said latch device and permitting the brush support to shift.

3. In a shoe-polishing machine, a rotatable support, a driving gear rotatable concentrically with the support, a plurality of rotatable brushes rotatable on the support, each of said brushes being geared to the driving gear, and automatically acting means for causing the support to rotate intermittently for placing the brushes successively in operative position.

4. In a shoe-polishing machine, two groups of brushes movable toward and from each other, and automatic means for shifting the brushes of each group so as to place them successively in operative position.

5. In a shoe-polishing machine, two groups of brushes movable toward and from each other for operating on opposite portions of a shoe, and means operating when the groups are moved apart for automatically shifting the brushes of each group and placing them successively in operative position.

6. In a shoe-polishing machine, brushes movable toward and from each other for operating on opposite sides of a shoe, a carrier movable toward and from the front of the shoe, a plurality of brushes on the carrier, and means operating when the carrier is away from the shoe for placing the brushes carried thereby in operative position successively.

7. In a shoe-polishing machine, the combination of a carrier movable toward and from the front of a shoe, a

- support rotatably mounted in the carrier, a plurality of rotating brushes carried by the support, means operating when the carrier is away from the front of the shoe for causing the brushes to move successively into operative position, and opposite side brushes movable toward and away from opposite sides of the shoe. 60
8. In a shoe-polishing machine, two groups of side brushes movable toward and from each other for operating on opposite sides of a shoe, means operating automatically when the brushes are away from the shoe for shifting the brushes of each group and placing them successively in operative position, a group of front brushes movable toward and from the shoe, and means for automatically shifting the front brushes for placing them successively in operative position. 65
9. In a shoe-polishing machine, groups of side brushes movable toward and from each other, automatic means operative when the groups are away from the shoe for shifting the brushes of each group and placing them successively in operative position; a group of front brushes movable toward and away from the shoe alternately with the movement of the side groups, and automatic means operating to shift the brushes of the front group when the latter is away from the shoe for placing the brushes thereof successively in operative position. 70
10. In a shoe-polishing machine, opposite groups of individually rotating brushes, each group being rotatably mounted for placing the brushes successively in operative position, a locking mechanism for each group for holding the same normally against rotation, a pair of levers—one for releasing each of the lock mechanisms, and lever operating mechanism. 75
11. In a shoe-polishing machine, opposite groups of individually rotating brushes, each group being rotatably mounted for placing the brushes thereof successively in operative position, locking mechanism for each group for holding the same normally against group rotation, levers for releasing said locking mechanisms, a rock shaft having a pair of arms—one for engaging and operating each of the said levers, a third arm projecting from the rock shaft, and a rotating member having a plurality of projections adapted successively to engage said third arm and oscillate the rock shaft. 80
12. In a shoe-polishing machine, two side groups of individually rotating brushes for operating on opposite portions of a shoe, each group being rotatably mounted, lock mechanism for each group for holding the same against group rotation, a front group of individually rotating brushes, said front group being rotatably mounted, lock mechanism for holding the same against group rotation, a rotating shaft, two series of projections on said shaft, mechanism actuated by the projections of one of the series for releasing the lock mechanisms of the side groups, and mechanism operated by the projections of the other series for releasing the lock mechanism of the front group. 85
13. In a shoe-polishing machine, a carrier movable toward and from the front of a shoe, a frame journaled at its center on a horizontal axis in the carrier, rotary brushes at opposite ends of the frame, gearing for rotating the brushes, a stop carried by each end of the frame, a spring-held catch on the carrier normally in the path of, and adapted to be engaged by, one or the other of said stops for preventing rotation of the brush-holder, and automatically acting means for so moving the catch as to permit the brush-holder to rotate. 90
14. In a shoe-polishing machine, the combination with the rotatable brush-holder having a stop at each end, and rotatable brushes at opposite ends of the holder, of the pivoted spring held latch having two stop-engaging surfaces—one in advance of the other, and means for so operating the catch as to cause it to present first one and then the other of said surfaces to each of said stops as they approach the same. 95
15. In a shoe polishing machine, the combination of a shoe support, a carrier movable toward and from a shoe resting on the support, the carrier being movable in the direction of the length of the shoe and in front of the said support, a shifting brush holder mounted in the carrier, and a plurality of brushes on the holder. 100
16. In a shoe polishing machine, the combination of a shoe support, a carrier mounted to oscillate on a horizontal axis and to move toward and from a shoe resting on the support, said movement being in the direction of the length of the shoe, a shifting brush holder mounted in the carrier, and a plurality of brushes carried by the holder. 105
17. In a shoe polishing machine, the combination of a shoe support, uprights adapted to oscillate toward and from the front of a shoe resting on the support, a vertically movable carrier extending from the uprights toward the shoe support, a shifting brush holder mounted in and movable vertically with the carrier, and a plurality of brushes carried by the holder. 110
18. In a shoe polishing machine, the combination of a shoe support, an oscillating carrier at each side of the support, the axes of the carriers extending longitudinally of the support, means for oscillating the carriers, a plurality of rotatable brushes mounted on each of the carriers with their axes parallel with the carrier axes, and brush rotating means. 115
19. In a shoe polishing machine, a series of groups of brushes, each group being operative on a given portion of a shoe, means for moving each group toward and from the shoe, means for shifting the brushes of each group when away from the shoe, brush operating means, and polish spraying mechanism operative intermittently and only when the brushes are away from the shoe. 120
- In testimony whereof we affix our signatures in presence of two witnesses.
- JOSEPH M. WOLKOSKY.
FRANK MAGIDSON.
SAMUEL PRINTZ.
ABRAHAM WOLKOSKY.
- Witnesses:
